SIMULATED WHEELED TOY CARTON

William P. Frankenstein, Cincinnati, Ohio

Application April 17, 1951, Serial No. 221,499

2 Claims. (Cl. 229—8)

This invention relates to improvements in knocked-down cartons and particularly to such cartons that when set up have the contour of, and by printing embellishments represent, wheeled toys.

The principal object of this invention is the provision of a wheeled toy-type carton which can be supplied to the user in knocked-down condition and readily set up for subsequent use.

Another object of this invention is the provision of a carton for accomplishing the foregoing object that by simple modification in the blank can be filled through, or has the closing member at, either the top or the sides, depending on the type and kind of merchandise to be packed and shipped therein.

A further object of this invention is the provision of a simulated wheeled toy formed to be used as a box or carton and in which the simulated wheels are judiciously cut from other portions of the box reducing the waste to a minimum.

A still further and specific object of the present invention is the provision of a box or carton shipped to the user in a knocked-down condition that when set up represents a piece of rolling stock of a railroad, a locomotive, a wheeled circus wagon, and the like, in which the said box or carton is supported on projections from the sides of the carton that have a semi-circular perimeter representative of wheels depending from the simulated prototype.

Specifically, it is an object of this invention to simplify the details of construction and assembly of cartons for accomplishing the foregoing objects and in which the carton can be produced economically and is inexpensive to acquire and erect enabling the use of said carton for the packing and shipping of inexpensive goods such as candies, cookies, and the like.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is an extended plan view of a blank from which one form of the carton of the present invention may be made.

Fig. 2 is a transverse sectional view through the blank of Fig. 1 after it has been folded and secured in said folded position and as shipped to the user.

Fig. 3 is a perspective view of an erected carton from the blank of Fig. 1.

Fig. 4 is a longitudinal sectional view through the erected carton of Fig. 3.

Fig. 5 is a transverse sectional view through the erected carton of Fig. 3.

Fig. 6 is an extended plan view of a modified form of the blank embodying the principals of Fig. 1.

2

Fig. 7 is a transverse sectional view through the folded and secured blank of Fig. 6 in the condition it is shipped to the user.

Fig. 8 is a perspective view of an erected carton formed from the blank of Fig. 6.

Fig. 9 is a longitudinal sectional view through the erected carton of Fig. 8.

Fig. 10 is a transverse sectional view through the erected carton of Fig. 8.

Fig. 11 is an extended plan view of a blank similar to Fig. 6 showing a slight modification over said Fig. 6.

Fig. 12 is a transverse sectional view through the folded and knocked-down blank of Fig. 11 as shipped to the user.

Fig. 13 is a perspective sectional view showing the carton from the blank of Fig. 11 at one stage of erection from its knocked-down position in Fig. 12.

Fig. 14 is a perspective sectional view, similar to Fig. 13, showing a further stage of erection of the carton from the blank of Fig. 11.

Fig. 15 is an extended plan view of a blank showing a further modification therein which may be erected to form a carton substantially identical in appearance with that of Fig. 8.

Fig. 16 is a transverse sectional view through the knocked-down or folded blank of Fig. 15 as shipped to the user.

Fig. 17 is a longitudinal sectional view through a carton erected from the blank of Fig. 15.

Fig. 18 is a longitudinal horizontal sectional view through the carton of Fig. 17 as seen from line 18—18 on said Fig. 17.

Fig. 19 is a transverse sectional view through the carton of Fig. 17 as seen from line 19—19 on said Fig. 17.

Fig. 20 is a view similar to Fig. 19 taken in a plane forwardly of that of said Fig. 19 on line 20—20 on Fig. 17.

Fig. 21 is a view similar to Fig. 16 of a folded knocked-down blank of Fig. 15 showing the said blank of Fig. 15 in an alternate knocked-down position from that of Fig. 16.

Fig. 22 is a plan view of a blank showing modifications therein that will produce a carton similar to the cartons produced by the above identified blanks.

Fig. 23 is a perspective view of an erected carton from the blank of Fig. 22.

Fig. 24 is a bottom plan view of the erected carton of Fig. 22.

Fig. 25 is a longitudinal sectional view of the erected carton of Fig. 23.

Fig. 26 is a transverse sectional view through the erected carton of Fig. 23.

Throughout the several views of the drawings similar reference characters are employed to denote the same or similar parts.

As was noted above, the chief object of the present invention is the provision of an inexpensive carton which simulates a wheeled toy and which may be produced from various specific blanks each having the basic underlying elements. The various blank modifications will be described in succession with the successive blanks merely having pointed out their modifications over the other blanks and the cartons resulting therefrom.

Accordingly, and referring first to Figs. 1 to 5, inclusive, use is made of a single blank cut or stamped from a piece of flat stock substantially rectangular in area and provided with a plurality of score or fold lines 31, 32, 33 and 34 thereby producing a plurality of adjacent integrally, hingedly, connected panels 36, 37, 38, 39 and 40.

In the erected carton the panel 36 forms the bottom and has its ends defined by score or fold lines 41 and

42 which respectively, hingedly connect to the ends of the panels 36 extensions 43 and 44 which in the erected carton form the end walls thereof. The blank of Fig. 1 upon erection produces the carton of Fig. 3 which after being suitably printed, as will hereinafter be pointed out, simulates a diesel locomotive having contoured or stepped ends, as will be presently described. For these reasons the extensions 43 and 44 are each provided with a pair of transverse score or fold lines 45 and 46 forming between them a transverse panel 47 and forming, in each extension, between the score or fold line 45 and score or fold line 41 an end wall section 48, and at the same time forming between the score or fold line 46 and the outer ends of said extensions 43 and 44 a second end wall section 49. The outer or free end of each of the end wall sections 49 is provided with a contour and is defined by diverging score or fold lines 50 and 51 which respectively, integrally, hingedly, connect with the said end walls, respectively, tucking tabs 52 and 53. The end walls extensions 43 and 44 are, respectively, each further provided with tucking tabs 54 and 55 integrally, hingedly connected with the ends of its panel 47. In view of the fact that the blank of Fig. 1 forms the locomotive, the score lines 41 and 42 which connect, respectively, the end walls extensions 43 and 44 to the bottom panel 36 each is provided with, intermediate its ends, angular cut lines 56 and 57, thereby providing at the bottom of each end wall extension a point 58 which in the erected carton form the cow-catcher or fender at the ends of the carton.

In the erected carton the panels 37 and 39 form the sides thereof and since they are substantially duplicates of one another it is deemed sufficient if but one of them be described in detail. Accordingly, the panel 37 has its ends contoured and formed in part by score or fold lines 59 and 60, and in part by score or fold lines 61 and 62 each of which inclines inwardly or toward the center of the blank. The score or fold lines 59 and 61, at one end of the blank, are joined by a horizontal cut line 63 while the score or fold lines 60 and 62, at the other end of the blank, are joined by a similar horizontal cut line 64. The score or fold lines 59 and 61 respectively, integrally, hingedly, connect with one end of the panel 37 tucking tabs 65 and 66, each of a different contour, for clearance purposes, with said tucking tab 66 having an edge 67 which has an inclination for a purpose later to be made clear. The score or fold lines 60 and 62 hingedly, integrally, connect with the other end of the panel 37 tucking tabs 68 and 69, similar to the tucking tabs 65 and 66, each having a relatively irregular outline with said tucking tab 69 having an angularly disposed edge 70 for a purpose to be subsequently made clear.

The outer longitudinal edge of the panel 37 is provided with semi-circular projections 71 formed by corresponding semi-circular cuts 72 in the panel 36 and with the score or fold line 31 joining said cuts 72. As shown in Fig. 1 there are four pairs of said semi-circular cuts 72, each pair being joined by a cut line 73 in a plane below that of the score or fold line 31. As will be seen in the other modifications the number of pairs of cut lines 72 may be varied depending upon the size of the carton and upon the number of wheels the vehicle being simulated has. It is for this reason that the specific blank of Fig. 1 has four such pairs of semi-circular cut lines which gives the impression of eight wheels, with each two wheels nearer one another forming a pair.

In the erected carton the panel 38 constitutes the roof and has its ends defined by straight cut lines with the said panel of somewhat greater length than the adjacent edges of the carton sides or blank panels 37 and 39, as respectively represented by the score or fold lines 32 and 33. The additional length of the panel 38 is employed to form projecting end edges of the roof, as is

usual practice in railroad rolling stock construction. The panel 38 is medially longitudinally divided by a score or fold line 74 thereby forming in the panel 38 a pair of adjacent panels 38a and 38b which in the erected carton form the inclining portions of the roof and respectively rest on the end walls inclined upper edges 51 and 50 respectively.

The remaining panel 40 of the blank in the erected carton forms a glue flap for adhesive and permanent attachment to the bottom panel 36. Said adhesive is indicated at 75 and is on the under surface of the blank as viewed in Fig. 1. The adhesive 75 extends longitudinally of the blank inwardly of each of its longitudinal edges so as not to interfere with the wheel projections 71 from the sides or panels 37 and 39 and to avoid adhesively connecting the said glue flap 40 to the said wheel projections 71.

The blank of Fig. 1 either at this time or previously had each of the outer faces of extensions 43 and 44, end walls, suitably printed, lithographed, or the like, as illustrated by the end of the carton of Fig. 3, so as to show a representation of a windshield on the section 49 of said end wall and the front end of the locomotive, fender, and coupler on the lower section 48 of said end wall. The carton sides or panels 37 and 39 are each printed, lithographed or otherwise illustrated, as in Fig. 3, to show the machinery compartment, windows for said compartment, the side of the operator's cab, and the other appurtenances of a locomotive or diesel engine. The panel 38 is likewise suitably printed to show or illustrate the usual top or roof of the said engine.

At this time the glue flap 40 has the adhesive 75 applied to the underside thereof, as seen in Fig. 1, whereupon the said glue flap is folded on the interrupted score or fold line 34, that is, the raising of the glue flap 40 allows the wheel projections at the outer edge of the panel 39 to remain in the plane of the said panel 39 while the glue flap is superimposed on the panel 39. If desired the adhesive 75 may now be applied to the now exposed surface of the glue flap 40, if the said adhesive had not been applied as above set forth. The blank is now folded on the score or fold line 32 for thereby bringing the glue flap or panel 41 into face contact with the carton bottom or panel 36 with the adhesive 75 therebetween. The usual pressure is now applied to the folded blank for adhesively connecting the glue flap and carton bottom to one another. The blank is now in its knocked-down position as illustrated in transverse cross-section in Fig. 2 and it is in this position that the carton is shipped to the user preparatory for erection and filling.

The user in desiring to erect or set up the carton does so by merely pressing on the right and left ends of the knocked-down blank as seen in Fig. 2 causing the top, bottom, and sides to swing on their score or fold lines to a substantially rectangular position whereupon one of the end walls, extension 43, for example, is raised and thereby projects the point 58 below the bottom 36 of the carton. The tucking tabs 65 from each of the side walls is now folded to be transversely of the carton and project inwardly, toward one another, from said sides, whereupon the end wall lower section 48 is pressed against the inclined ends 59 of the side walls. The tucking tabs 54 and 55 of the end wall panel 47 are then folded to be normal to the said panel 47 and the said panel 47 actuated about the score or fold line 45 toward the side walls end horizontal cuts 63 and the tucking tabs 54 and 55 inserted within the carton behind the tucking tabs 65. Side wall tucking tabs 66 are then folded to be normal to the side walls and transversely of the carton.

This adjustment of the tucking tabs 66 causes their inclined upper edges 67 to underlie the top panel sections or panels 38a and 38b to hold said sections panels in positions that they incline outwardly of one another from the longitudinal medial score line 74 in the roof panel 38. The end wall or extension 43 then has its tucking

tabs 52 and 53 folded to be substantially normal to the end wall upper section 49 whereupon the said end wall upper section 49 is actuated toward the carton side walls inclined edges 61 and the tucking tabs 52 and 53 are inserted within the carton to be between the inclined edges 67 of the tucking flaps 66 and the roof sections 38a and 38b. At this time the upper end of the end wall upper section, as represented by the score or fold lines 50 and 51, underlies the roof panel inwardly of its end and retains the said roof panel sections 38a and 38b in their inclined positions. The box or carton is now sufficiently set up that it can be filled through its other end. After the merchandise has been placed in the carton, the second end, extension 44, is closed in the same manner as the first end, extension 43, was closed.

The filled carton is now as illustrated in Fig. 3 and may be stood on the semi-circular projections 71 which have been printed to represent wheels so that the carton simulates a wheeled vehicle, a diesel locomotive or engine.

The chief distinction between the blank of Fig. 6 and the blank of Fig. 1 is that the ends of the carton resulting from the blank of Fig. 6 are normal to the top, bottom and sides and the carton of Fig. 8 has but four projections or wheel simulations instead of eight as illustrated in Fig. 3. For these reasons the end wall extensions 43' and 44' of Fig. 6 have no transverse score or fold lines and are solid members with their outer ends defined by the inclined score or fold lines 50 and 51 for the tucking tabs 52 and 53.

The side walls or panels 37' and 39' instead of having contoured ends have substantially vertical ends and are respectively defined by score or fold lines 76 and 77 which integrally, hingedly, connect with the ends of the said side walls single tucking flaps 78 and 79.

The blank is suitably printed to simulate a piece of rolling stock, such as a freight car, by having the end wall panels or extensions 43' and 44' printed as freight car ends, the panels 37' and 39' printed as freight car sides, and the panel 38 printed as a freight car top. The blank is then folded and secured in its folded or knocked-down position as illustrated in Fig. 7 for shipment to the user. The user in desiring to set up and fill the carton with merchandise follows substantially the same steps as outlined above with the result of a carton as illustrated in Fig. 8.

The blank of Fig. 11 is substantially identical with the blank of Fig. 6 except that the glue flap 40' of Fig. 11 is provided longitudinally with a score or fold line 80. By this construction the blank may be knocked-down or folded so as to break all of the semi-circular projections or wheel representations from the panels from which they are cut, and in some instances thereby assist in erecting the carton. This is accomplished by placing the adhesive 75 in the position of the blank as illustrated in Fig. 11, that is, outwardly of the longitudinal medial score or fold line 80 but inwardly of the end of the blank when the blank inner face is uppermost, as seen in Fig. 11. In assembling the blank the glue flap 40' is folded on itself along the score or fold line 80 to have the outer faces of the glue flap in contact whereupon the steps above set forth are followed, that is, the now folded glue flap is further folded on the score or fold line 34 to bring the portion of the glue flap devoid of adhesive on top of the panel 39' whereupon the blank is further folded on the roof medial score or fold line 74, instead of on the score or fold line 32. Prior to the folding of the blank on the score or fold line 74 the panel 36 was folded to be superimposed on the panel 37' wherefore the adhesive 75 engages with the surface of the blank normally the outer surface of the carton, and pressure is then applied for adhesively securing the glue flap 40' with the carton bottom or panel 36 of the blank. The blank is now in its folded or knocked-down

position as transversely illustrated in section in Fig. 12.

As will be seen, the wheels simulations from each of the carton sides are now projecting from the knocked-down blank and the user in desiring to set up the said carton applies pressure to the right and left-hand ends of the knocked-down blank as seen in Fig. 12. As the pressure is applied the carton passes through the stage illustrated in Fig. 13 with the bottom of the carton folding from its superimposed position against the inner surface 10 of the carton side to a position to be normal thereto and which is the position of the bottom when the carton is fully set up having a substantially rectangular cross-section as illustrated in solid and phantom lines in Fig. 14. The erection of the end walls, extensions 43' and 44' 15 cause the roof or carton top panel to have inclined portions such as illustrated in Figs. 8 and 10.

The modified blank and the carton formed therefrom as illustrated in Figs. 15 to 21 is quite similar to the blanks of Figs. 6 and 11 and results in a carton which, when erected, is barely distinguishable from that illustrated in Fig. 8. The chief distinction between the blank of Fig. 15 and the blank of Fig. 6 is that the end walls of the carton from the blank of Fig. 15 are carried by the side walls, instead of the bottom, and swing or oscillate 25 from side to side of the carton, instead of from bottom to top. This construction has necessitated a slight rearrangement of the panels with respect to the ends of the blank, and the placement of the glue flap at an edge of the carton bottom instead of at the edge of a carton 30 side, as illustrated with each of the foregoing blanks.

Specifically, the side of the carton or panel 37' is illustrated as having integrally, hingedly connected with its one end by a score or fold line 77, the end wall extension or panel 81 having at its free end integrally, 35 hingedly connected therewith a tucking or locking tab 82. The upper end of the panel 81 is pyramidal formed or provided with inclined score or fold lines 50 and 51 for integrally, hingedly connecting therewith the tucking tabs 52 and 53. The other end of the carton 40 side or panel 37' is provided, in part, by a cut line and in part by a score or fold line 76' for integrally, hingedly connecting a tucking tab 78'. It should be noted that if desired the said score or fold line 76' may be the full height of the carton side for connecting therewith a 45 panel 81 to form the second end wall of the carton, in the specific blank illustrated in Fig. 15 the said second end wall is carried by the other carton side or panel 39'. It will further be noted that in this specific form of the blank the carton side wall or panel 37' is the end of the blank and has projecting from it the wheel simulations 71.

The side wall panel 39' has its end defined by the score or fold line 77 through which is integrally, hingedly, connected therewith a flap 83 which is substantially of the area and contour of the end wall extension or panel 81 and in the erected carton backs up the said carton end wall extension or panel 81 by being in face contact therewith as shown clearly in the left-hand ends of Figs. 55 17 and 18. The score or fold line 77 at the end of the panel 39' is provided intermediate its ends with a slit 84 through which is pushed the locking tab 82 of end wall extension or panel 81 in securing the carton in its erected position. The other end of the carton side or blank panel 39' is defined by the score or fold line 76 and has integrally, hingedly, connected therewith an end wall extension or panel 85 which is substantially identical with the end wall extension or panel 81 having its upper end pyramidal formed and defined by inclined 60 score or fold lines 50 and 51 which respectively integrally, hingedly connect therewith tucking tabs 52 and 53. The free end of the end wall extension or panel 85 has integrally, hingedly connected therewith the locking tab 82 with said locking tab displaced with respect to the free end of said end wall by comparison with the locking tab of the end wall 81.

The modified blank of Fig. 15 has the ends of its bottom panel defined by the score or fold lines 41 and 42 which integrally, hingedly connect therewith tabs 86 and 87 that upstand therefrom, in the erected carton, and form abutments for the end wall panels 81 and 85 as illustrated in Figs. 17 and 19. The bottom panel 36' of the modified blank of Fig. 15 similar to the supplemental bottom panel or glue flap 40' of Fig. 11 is longitudinally scored at 88 with said scores extending through the contiguous tabs 86 and 87. This bottom panel 36', similar to the bottom panels of the above identified blanks, is provided with the semi-circular cuts 72 to provide the semi-circular projections or wheels simulations 71 for the carton side or panel 39'.

Projecting from the panel 36' and integrally, hingedly connected therewith is the glue flap 40'' which, as noted above, and as seen most clearly in Figs. 19 and 20, instead of being adhesively secured to the carton bottom is adhesively secured to the inner surface of the carton side or blank panel 37'.

The blank of Fig. 15 may be folded into its knocked-down form in either of two ways, respectively illustrated in Figs. 16 and 21. As illustrated in Fig. 16 the blank is folded substantially through the steps that Fig. 11 was folded with the adhesive 75 thereon applied to the upper surface of the blank as illustrated in Fig. 15. This folding of the blank comprising rearwardly bending the glue flap 40'' on the score or fold line 34, forwardly folding the bottom panel 36' on its medial score or fold line 88 and then folding the blank on the roof medial score line 74. This results, as noted above, in the knocked-down carton as illustrated in transverse section in Fig. 16. To erect the carton the user merely applies pressure to the right and left-hand ends of the folded blank of Fig. 16.

To obtain the knocked-down blank of Fig. 21 the adhesive 75 is applied to the under surface of the glue flap 40'', in the position as illustrated in Fig. 15, whereupon the blank is folded on the bottom panel medial score line 88 for superimposing the bottom panel sections, on either side of said medial score line, on one another and superimposing the glue flap on the carton side or blank panel 39'. The blank is then folded on the roof medial score line 74 into the position of Fig. 21. The user in desiring to erect the carton merely applies pressure to the right and left-hand ends of the knocked-down blank of Fig. 21 as above set forth in connection with the other modified blanks.

In each of the foregoing modifications of the invention it will be observed that the carton after erection is filled, or has contents placed therein, through an end wall which is then frictionally locked in place. The inventive thought of the present invention may be applied to a box or carton which has its upper end or roof hingedly connected with the side wall for opening and closing and frictionally held in the closed position. Such a carton is illustrated in Figs. 22 to 26, inclusive, and will now be described in detail.

The blank in Fig. 22 has the side and end wall panels hingedly connected with one another instead of the side walls and top and bottom panels resulting in the blank having a somewhat greater dimension in one direction than in the other as distinguished from the above blanks which are substantially square in area. Accordingly, the blank of Fig. 22 is provided with transverse score or fold lines 89, 90, 91 and 92 hingedly connecting to one another panels 93, 94, 95, 96, and 97. The panels 93 and 95 form the end walls of the carton and each has its upper end pyramidal formed or defined by inclined score lines 56 and 51 for integrally, hingedly, connecting therewith tucking tabs 52 and 53. Each of these end walls has its lower end defined by a score or fold line 98 for integrally, hingedly, connecting therewith a locking tab and bottom portion 99 each of which has, in turn, projecting therefrom a locking lug 100.

Each of the panels 94 and 96 forms in the carton a

side wall and each having its lower end defined by a score or fold line 101 for integrally, hingedly connecting therewith a bottom panel portion 102. The side wall 94 panel portion 102 has laterally projecting from it, near its free ends, locking lugs 103 and 104 while the bottom panel portion 102' of the side wall panel 96, has downwardly projecting locking lugs 105 and 106.

The side wall panel 94 has its upper end defined by a score or fold line 107 for integrally, hingedly, connecting therewith the top panel 38, similar in all respects with that above described. The free end of the top panel 38 has connected therewith through a score or fold line 108 the tucking flap 109. The said carton top or panel 38 is provided with a medial score line 74 thereby providing in the said top panel 38 additional panels 38a and 38b which in the erected carton form the inclined sides of the carton top or roof.

After the blank of Fig. 22 has been cut and scored as above described it is then suitably imprinted to simulate a wheeled vehicle such as illustrated in Fig. 8 or some other vehicle such as a circus wagon having two wheels projecting from each of the carton side walls. The blank is then arranged in its knocked-down position by folding the glue flap 97 on the score or fold line 92 to be superimposed on the carton side or panel 96. This folding of the glue flap is accomplished either after the adhesive 110 has been applied to the under surface thereof, as seen in Fig. 22, or said adhesive is applied after the folding. The blank is then further folded on the score or fold line 90 to bring the adhesive 110 into contact with the other carton end wall or panel 93. It is in this condition that the knocked-down blank is shipped to the user.

The user upon desiring to set up the carton first opens the carton to be rectangular in plan, that is, have the sides and end walls extending normal to one another as illustrated in Fig. 24, whereupon the bottom portions or sections are locked in position.

In order to lock up the said bottom, the bottom flap or portion 102' is first bent on its score or fold line 101 to be normal to its side wall panel 96. The end walls bottom portions or flaps 99 are then folded to be normal to their respective end walls and overlie the adjacent ends of the said bottom panel or portion 102'. The remaining bottom portion or panel 102 is now folded to be normal to its side wall panel 94 and is pushed against the overlying bottom panels or portion 99 and 102' until the locking lugs 103 and 104, of the bottom portion or panel 102, is pushed below the opposite bottom portion or panel 102'. By this operation the locking lugs 100 of each of the bottom panels or portions of the end walls are forced below the bottom portion or panel 102' so that they underlie the part of the bottom portion or panel 102' that is between its locking lugs 105 and 106 to be beneath the end walls bottom portions or flaps 99. Simultaneously the locking lugs 103 and 104 of the bottom portion or flap 102 is inserted beneath the overlapped portions of the other bottom portions or flaps 99 and 102' thereby securely interengaging the parts with one another with the various locking lugs of the bottom portions interlocked and overlying one another as clearly illustrated in Figs. 24 and 26.

At this time the carton may be filled through its open upper end whereupon the cover or roof panel 38 is actuated about the score or fold line 107 for closing the said top of the carton and the top is held in closed position by inserting the tucking flap 109 into the carton.

From the foregoing it will be noted that each of the above modifications produces a carton which is substantially rectangular in plan view and includes side walls having integral therewith semi-circular projections which by printing represent wheels depending below the bottom of the carton and acting as supports for said carton.

The said wheels are cut or died from the portions of the carton blank which forms all or part of the bottom for the carton. Each of the said cartons is provided with one or more swinging flaps adapted to be closed and frictionally retained in closed position for enabling access to the interior of the carton for the placement therein of merchandise.

Each of the above cartons by judicious printing gives the simulation of a wheeled vehicle, such as pointed out above, a locomotive, a piece of rolling stock such as a freight car, a circus wagon, and may produce any other type of a vehicle movable on wheels such as trucks, milk delivery trucks or wagons, and the like.

What is claimed is:

1. A carton simulating a piece of railroad rolling stock of the class described formed from a single blank including opposed side walls, opposed top and bottom, a glue flap from one side wall adhesively attached to the bottom providing a tube-like carton which may be folded flat with the side walls, top and bottom superimposed on one another as a knocked-down carton for shipment, end walls integrally, hingedly, attached to the ends of and upstanding from the bottom to and beneath the top closing the ends of the carton said top being of such length that the ends thereof respectively project beyond the end wall therebeneath, semi-circular projections from the side walls projecting below the bottom for supporting the carton, said side walls each having, at least, a similar end similarly provided with inclined and stepped portions intermediate its height, said end wall at the ends of the side walls provided with inclined and stepped portions having portions for following the inclined and stepped portions of the side walls ends.
